[57] CLAIM

The ornamental design for a display fixture, as shown and described.

DESCRIPTION

FIG. 1 is a top, front, and left side perspective view of a display fixture showing our new design, the fragmentary broken-line depiction of goods displayed being for illustrative purposes only and forming no part of the claimed design;

FIG. 2 is a top plan view thereof;

FIG. 3 is a bottom plan view thereof;

FIG. 4 is a left side elevational view thereof, the right side being a mirror image of that shown;

FIG. 5 is a front elevational view thereof; and

FIG. 6 is a rear elevational view thereof.
